UNITED STATES PATENT OFFICE.

DAVID CROMWELL, OF ST. LOUIS, MISSOURI.

IMPROVEMENT IN REFRIGERATORS.

Specification forming part of Letters Patent No. 119,508, dated October 3, 1871.

To all whom it may concern:

Be it known that I, DAVID CROMWELL, of St. Louis, in the county of St. Louis and State of Missouri, have made a certain new and useful Improved Refrigerator; and I do hereby declare that the following is a full and true description thereof, reference being had to the accompanying drawing and to the letters of reference marked thereon.

This invention consists in a new arrangement of ice-chamber in combination with provision-chambers, the ice-chamber being constructed to form an L-shaped ice receptacle round the top and at one side of said provision-chambers; and also in certain detail construction of parts, all of which will now more fully appear.

To enable those herein skilled to make and use my said improvements, I will now more fully describe the same, referring to—

Figure 1 as a top-sectional plan at line $x y$; Fig. 2 as a longitudinal sectional elevation at line $x^1 y^1$; Fig. 3 as a transverse sectional elevation at line $x^2 y^2$.

The chest or box A of the refrigerator is constructed as usual, having hinged door B on top, front doors $B^1 B^2$. Also, said box and doors are packed or fitted as usual, with suitable non-conducting material. Each of the doors $B B^1 B^2$, however, have thin closing edges fitted with rubber strips, b, to form air-tight fit. The interior of the box A will be lined with galvanized metal. The interior chamber is divided by top ice-chambers C, the lower chamber being further divided by a partition, c, to form provision-chambers $C^1 C^2$. The division between ice-chamber C and the said provision-chambers being made by an L-shaped ice-chamber or receptacles, d d' , round the back and side of an elevated ice-floor or support, D, in manner illustrated in the figures. Said ice-floor D (forming also main top of chambers $C^1 C^2$) has its top and sides constructed slanting

backward, to conduct the water back to L-shaped chamber. (See Fig. 3.) It will be noticed that on top said ice-floor D the ice can be stored in large cakes and thus kept to last a longer time; also, the L-shaped chamber is fitted with ice. Thus, by supporting the ice on top and arranging the L-shaped ice-chamber round the back and side of the provision-chambers $C^1 C^2$, the same receive all the benefits of the refrigeration process in the ice-chamber proper. Furthermore, by means of the side ice-chamber d a perfect "freeze" can be obtained in its contiguous provision-chamber C^1 , and a "chill" in the provision-chamber C^2 to accommodate the kinds of provisions to be kept. To strengthen the ice-flooring D the same has attached or soldered stays d^2 , and these are further utilized by hooks d^3 . The interior of such provision-chamber is provided with shelves, as ordinarily. To the back of the ice-chamber C is a cooler, E, for ice-water. It has the hinged door e. The water-pipe F communicates with the bottom of the cooler, its stop-cock f being in front. The exhaust or waste-pipe F' connects with the L-shaped ice-chamber, passing out at the bottom. The arrangement of each of said pipes F F' is made to pass through the provision-chamber C^2 to prevent freezing of the pipes, and as clearly shown in Fig. 3.

Having thus fully described my said improvements, what I claim is—

In combination with the provision-chambers $C^1 C^2$, the ice-chamber C, its slanting ice-support D, provided with stays $d^2 d^3$, and the L-shaped ice-receptacle $d d'$, all constructed and arranged substantially as and for the purposes described.

In testimony of said invention I have hereunto set my hand.

DAVID CROMWELL.
